**LIGHTOUT PROTECTION FOR 3-BLOCK
4-INDICATION SIGNALLING SYSTEM**

Arthur E. Dodd, Edgewood, Pa., assignor to Westinghouse Air Brake Company, Wilmerding, Pa., a corporation of Pennsylvania

Application October 25, 1951, Serial No. 253,156

10 Claims. (Cl. 246—50)

My invention relates to a railway signal control system. More particularly, my invention relates to a lightout protection scheme for a railway signaling system which embodies light signals of such, for example, as the well-known searchlight type.

Lightout protection schemes have previously been devised for steady light aspects in two-block indication signaling systems embodying signals of the color light type or of the searchlight type.

An object of my invention is the provision of a lightout protection arrangement for a railway signaling system in which the signals are normally not lighted but are controlled to become lighted in response to the approach of a train, and in which each signal at times displays a flashing light aspect.

A feature of my invention for accomplishing this object is an arrangement in which a lightout relay has a high resistance winding and a low resistance winding energized by pickup circuits including front and back contacts respectively of an approach relay and energized alternately by stick circuits while a flashing light signal aspect is being displayed.

I shall describe two forms of apparatus embodying my invention, and shall then point out the novel features thereof in claims.

In the accompanying drawings, Figs. 1a and 1b, when placed end to end, with Fig. 1a on the left, constitute a diagrammatic view showing one form of apparatus embodying my invention, in which a lightout relay having a high resistance winding and a low resistance winding is provided for each signal in a three-block four-indication signaling system; in which each signal is of the searchlight type; in which each signal is normally not lighted, but is controlled to become lighted in response to an approaching train; and in which each signal at times displays a flashing light aspect.

Fig. 2 is a diagrammatic view showing a modified form of the apparatus associated with each signal in Fig. 1, also embodying my invention, in which provision is made for normally lighting each signal by alternating current energy, and for lighting each signal by direct current energy in the event of failure of the alternating current source.

Similar reference characters refer to similar parts in each of the views.

Referring further to Figs. 1a and 1b of the drawings, a stretch of railway track is shown, over which traffic movements are normally made in the direction indicated by the arrow. In order to simplify the drawings, each track, comprising two parallel series of track rails, is represented by a single line.

The stretch of track is divided by insulated joints 5 into sections designated by the reference characters 0T, 1T, 2T, and 3T. A portion of a section, designated by the reference character 4T, is also shown at the right-hand end of Fig. 1b. Each of the sections 0T, 1T, 2T and 3T is provided with a track circuit including a suitable source of current such, for example, as a battery 6,

2

connected across the rails adjacent one end of the section, and a track relay, designated by the reference character R preceded by the reference character for the corresponding section, connected across the rails adjacent to the opposite end of the section.

Signals, designated by the reference characters 1S, 2S, 3S and 4S, are located adjacent the entrance end of sections 1T, 2T, 3T and 4T, respectively, for governing traffic movements toward the right, as shown in the drawings, which I shall assume is the eastbound direction. The length of track between each signal and the next signal in advance is known as a block, and therefore each of the sections 0T, 1T, 2T and 3T constitutes a block.

Each of the signals, as shown in the drawings, is of the well-known searchlight type such, for example, as shown in Letters Patent of the United States No. 1,864,224, granted June 21, 1932, to Wesley B. Wells, for Light Signals. Each of the signals has a mechanism, designated by the reference character G preceded by the numeral in the reference character for the corresponding signal, and has a lamp, designated by the reference character E preceded by the numeral in the reference character for the corresponding signal. The mechanism G of each signal operates a spectacle in which there are three filters which may be of the colors, green, yellow and red, respectively. When the mechanism G for a signal is energized by current of normal polarity, the mechanism G moves the green filter in front of the lamp E, so that the signal displays a green aspect; when the mechanism G is energized by current of reverse polarity, it moves the yellow filter in front of the lamp E, so that the signal then displays a yellow aspect; and when the mechanism G is deenergized, it moves the red filter in front of the lamp E, so that the signal then displays a red aspect.

In the arrangement shown in the accompanying drawings, each of the signals is controlled to display three different proceed indications, as well as a stop indication, in a three-block, four-indication signaling system, as shown by the following tabulation:

Name of Signal Indication	Signal Indication	Signal Aspect
Clear	Proceed	Steady green light.
Advance Approach	Proceed, preparing to stop at second signal in advance.	Flashing yellow light.
Approach	Proceed, preparing to stop at next signal.	Steady yellow light.
Stop	Stop	Steady red light.

The mechanism G of each signal is controlled by a home control relay, designated by the reference character HR preceded by the numeral in the reference character for the corresponding signal, and by a distant control relay, designated by the reference character HDR preceded by the numeral in the reference character for the corresponding signal. Each relay HDR is of the retained neutral type, that is, its front contacts are slow releasing and remain closed during a reversal of polarity of the current supplied to the control winding of the relay.

An approach control relay for the lamp for each signal is designated by the reference character AR preceded by the numeral in the reference character for the corresponding signal. Each approach control relay AR is controlled by a front contact of the track relay for the first block in the rear of the corresponding signal and by a front contact of the track relay for the first block in advance of the corresponding signal.

The home control relay HR for each signal is controlled by a front contact of the track relay for the first

block in advance of the corresponding signal, and by a front contact of a lightout relay, designated by the reference character LOR preceded by the numeral in the reference character for the corresponding signal.

Each lightout relay LOR has two control windings, one of which I shall call the first winding, designated by the reference character 1000, having a high resistance which may be of the order of 1000 ohms, and the other winding which I shall call the second winding, designated by the reference character 0.58, having a low resistance which may be of the order of 0.58 ohms.

Each distant control relay HDR is controlled by a front contact of the home control relay HR for the corresponding signal, and by a front contact of the relay HR for the first signal in advance of the corresponding signal, and also by pole-changing contacts of the HR relay for the second signal in advance of the corresponding signal.

A flashing yellow control relay for each signal is designated by the reference character FYR preceded by the numeral in the reference character for the corresponding signal. Each relay FYR is controlled by a front contact and by a reverse polar contact of the HDR relay for the corresponding signal.

A flasher relay for each signal is designated by the reference character FR preceded by the numeral in the reference character for the corresponding signal. Each relay FR is of a type which, while it is energized, will repeatedly close and open its front and back contacts alternately at a frequency which may be of the order of 40 times per minute.

Each relay LOR has pickup circuits for its high and low resistance windings controlled over front and back points, respectively, of contacts of the AR relay for the corresponding signal, and has stick circuits for these windings which are repeatedly closed alternately 40 times per minute by front and back contacts, respectively, of the FR relay for the corresponding signal. Each relay LOR is made slow releasing by an asymmetric unit, designated by the reference character *i*, which may be of the well-known halfwave copper oxide rectifier type, connected across the low resistance winding of the LOR relay in a direction to oppose the flow of current in multiple with the low resistance winding of the LOR relay.

The lighting of lamp E for each signal is controlled by the relays AR, FYR, FR and LOR for the corresponding signal. Each lamp E is at times connected in series with the high resistance winding of the LOR relay for the corresponding signal, and is at other times connected in series with the low resistance winding of the LOR relay for the corresponding signal. The relation between the resistances of the windings of the LOR relays and the lamps E is such that, when a lamp E is connected in series with a high resistance winding, the lamp will not be lighted but will remain dark, and when a lamp E is connected in series with a low resistance winding, the lamp will be lighted.

An energy storing device for each signal, shown as a capacitor designated by the reference character *c*, is controlled to become charged by a circuit which includes a front contact of the LOR relay for the corresponding signal and a back contact of the flasher relay for the corresponding signal. When the flasher relay closes its front contact, the capacitor will then discharge through the high resistance winding of the corresponding LOR relay for retaining the LOR relay in the picked-up condition.

The control circuits and lamps may be supplied with energizing current by any suitable source such, for example, as a battery shown in Fig. 1a, designated by the reference character Q and having terminals B and N.

In the modified form of apparatus shown in Fig. 2, all parts of the apparatus shown in Figs. 1a and 1b are controlled as in Figs. 1a and 1b except that the energizing circuits for the lamps E in series with the low resistance windings 0.58 of relays LOR are modified so that nor-

mally they are supplied with alternating current, and are supplied with direct current when the source of alternating current fails. The source of alternating current may be a generator, designated by the reference character ACG, as shown in Fig. 2 having terminals BX and NX.

A power-off relay, designated by the reference character POR, is connected directly across terminals BX and NX, and is therefore normally energized, but becomes deenergized when the alternating current source fails.

10 Alternating current is normally supplied from generator ACG through front points of contacts of relay POR, and direct current is supplied from a battery Q through the back points of these contacts, when the alternating current source fails.

15 Having described, in general, the arrangement and control of the various parts of apparatus embodying my invention, I shall now describe the circuits and operation in detail.

20 As shown in the drawings, all parts of the apparatus are in the normal condition, that is, the stretch of track is unoccupied, and therefore the track relays are all energized; the mechanism G of each of the signals is energized by current of normal polarity, and therefore each mechanism G is in the clear proceed position, with the green 25 filter in front of the lamp E which is, however, not lighted; relays 1HDR, 2HDR and 3HDR are energized by current of normal polarity; relays 1AR, 2AR, 3AR, 1HR, 2HR and 3HR are energized; the high resistance winding of each of the relays 1LOR, 2LOR and 3LOR 30 is energized in series with the lamp E for the corresponding signal, and therefore the lamps E are not lighted; relays 1FYR, 2FYR, 3FYR, 1FR, 2FR and 3FR, and the low resistance winding of each of the relays 1LOR, 2LOR and 3LOR are all deenergized; and the power-off 35 relay POR, shown in Fig. 2, is energized.

Relay 1AR is energized by a circuit passing from terminal B, through contacts 7 and 8 of relays 0TR and 1TR, respectively, and the winding of relay 1AR to terminal N. Each of the relays 2AR and 3AR is energized by a similar circuit which includes front contacts 40 of the track relays for the first block in the rear and the first block in advance of the corresponding signal.

Relay 1HR is energized by a circuit passing from terminal B, through contacts 13 and 14 of relays 1TR and 45 1LOR, respectively, and the winding of relay 1HR to terminal N. Each of the relays 2HR and 3HR is energized by a circuit which is similar to the circuit just traced for relay 1HR, which includes a front contact of the track relay for the first block in advance of the corresponding signal and a front contact of the lightout relay for the 50 corresponding signal.

The circuit by which relay 1HDR is energized by current of normal polarity passes from terminal B, through the front point of contact 19 of relay 3HR, front 55 contacts 20 and 21 of relays 2HR and 1HR, respectively, the winding of relay 1HDR, and the front point of contact 22 of relay 3HR to terminal N. Each of the relays 2HDR and 3HDR is energized by current of normal polarity in a circuit which is similar to the circuit just 60 traced for relay 1HDR, but only a portion of which is shown in the drawings.

Mechanism 1G is energized by current of normal polarity passing from terminal B, through contact 25 of relay 1HR, front neutral contact 26 of relay 1HDR, normal 65 polar contact 27 of relay 1HDR, mechanism 1G, and contacts 28 and 29 of relay 1HDR to terminal N. Each of the mechanisms 2G and 3G is energized by a circuit which is similar to the circuit just traced for mechanism 1G.

70 The high resistance winding of relay 1LOR is energized by a circuit passing from terminal B, through the high resistance winding of relay 1LOR, front point of contact 43 of relay 1AR, and lamp 1E to terminal N. Lamp 1E, however, on account of being connected in 75 series with the high resistance winding of relay 1LOR,

remains unlighted. The high resistance windings of relays 2LOR and 3LOR, and lamps 2E and 3E, are energized by circuits which are similar to the circuit just traced for the high resistance winding of relay 1LOR and lamp 1E, and therefore each of the lamps 2E and 3E is also unlighted.

In the arrangement shown in Fig. 2, the high resistance winding of relay 1LOR is energized by a circuit passing from terminal B, through the high resistance winding of relay 1LOR, front point of contact 68 of relay 1AR lamp 1E, and the front point of contact 69 of relay 1AR to terminal N. Relay POR, shown in Fig. 2, is constantly connected across terminals BX and NX, and is therefore energized at all times except when the source of alternating current fails.

I shall assume that, with apparatus arranged as shown in Figs. 1a and 1b of the accompanying drawings, an eastbound train enters section 0T, deenergizing relay 0TR. Contact 7 of relay 0TR will then open the circuit traced for relay 1AR, causing relay 1AR to be deenergized.

With relay 1AR deenergized, the energizing circuit for the high resistance winding of relay 1LOR will be opened at the front point of contact 43 of relay 1AR, and the pickup circuit for the low resistance winding of relay 1LOR will be completed at the back point of contact 43 of relay 1AR, this circuit passing from terminal B, through the back point of contact 42 of relay 1FYR, the low resistance winding of relay 1LOR in multiple with asymmetric unit i, back point of contact 43 of relay 1AR, and lamp 1E to terminal N. Lamp 1E, upon being connected in series with the low resistance winding of relay 1LOR, will become lighted. As previously described, mechanism 1G is energized by current of normal polarity, so that the green filter is in front of lamp 1E, and therefore signal 1S will now display the steady green light aspect.

When the train enters section 1T, deenergizing relay 1TR, contact 9 of relay 1TR will open the circuit for relay 2AR, causing relay 2AR to be deenergized, so that lamp 2E of signal 2S will then become lighted, and signal 2S will be controlled to display the steady green light aspect similarly to signal 1S, as previously described, in response to the train entering section 0T.

Also, with relay 1TR deenergized, contact 13 of relay 1TR will open the circuit for relay 1HR, and contact 8 of relay 1TR will open the circuit for relay 1AR at another point. With relay 1HR deenergized, the circuit for relay 1HDR will be opened at contact 21 of relay 1HR, and the circuit for mechanism 1G will be opened at contact 25 of relay 1HR, so that relay 1HDR and mechanism 1G will both be deenergized. Mechanism 1G will therefore move the associated spectacle to the position in which the red filter is in front of lamp 1E, and therefore, with lamp 1E lighted, signal 1S will now display the steady red light aspect. As long as the train remains on section 1T, relays 1HR and 1AR will be deenergized, and therefore signal 1S will continue to display the steady red light aspect as long as the train occupies block 1T.

When the train enters section 2T, deenergizing relay 2TR, relay 3AR will be deenergized by the opening of contact 11 of relay 2TR, so that lamp 3E will be lighted and signal 3S will be controlled to display the steady green light aspect similarly to signals 1S and 2S, as previously described, in response to the train entering sections 0T and 1T, respectively.

With relay 2TR deenergized, signal 2S will display a steady red light aspect, as previously described for signal 1S in response to the train entering section 1T, and will continue to do so as long as the train occupies block 2T.

When the train leaves section 1T, relay 1AR will again become energized by its circuit previously traced. With relay 1AR again energized, lamp 1E will be connected in series with the high resistance winding of relay 1LOR in the circuit previously traced, and therefore lamp 1E will become extinguished. Relay 1HR will again be

energized by its circuit previously traced, but relay 1HDR will now remain deenergized on account of its circuit being open at contact 20 of relay 2HR. With relay 1HR energized and with relay 1HDR deenergized, mechanism 1G will now be energized by current of reverse polarity passing from terminal B, through contact 25 of relay 1HR, back point of contact 26 of relay 1HDR, mechanism 1G, and the back point of contact 29 of relay 1HDR to terminal N. With mechanism 1G energized by current of reverse polarity, mechanism 1G will move its spectacle to the position in which the yellow filter will be in front of lamp 1E, but since lamp 1E is now extinguished, signal 1S will remain dark.

When the train enters section 3T, deenergizing relay 3TR, contact 17 of relay 3TR will open the circuit for relay 3HR, causing relay 3HR to also be deenergized. Signal 3S will therefore display the steady red light aspect, as previously described for signals 1S and 2S.

When the train leaves section 2T, relay 2AR will again become energized by its circuit previously traced, and lamp 2E will be connected in series with the high resistance winding of relay 2LOR, as previously described, so that lamp 2E will be extinguished. Relay 2HR will now again be energized by its circuit previously traced, but relay 2HDR will be deenergized on account of contact 23 of relay 3HR being open. Mechanism 2G will therefore be energized by current of reverse polarity, as previously described, for signal 1S.

With relays 1HR and 2HR again energized and relay 3HR deenergized, relay 1HDR will now be energized by current of reverse polarity in a circuit which is the same as the circuit previously described for this relay except that it includes the back points of contacts 19 and 22 of relay 3HR instead of the front points of these contacts.

With relay 1HR energized and with relay 1HDR energized by current of reverse polarity, mechanism 1G will now be energized by current of reverse polarity in another circuit passing from terminal B, through contact 25 of relay 1HR, front point of contact 26 of relay 1HDR, contact 27 of

relay 1HDR closed in the reverse position, mechanism 1G, contact 28 of relay 1HDR closed in the reverse position, and the front point of contact 29 of relay 1HDR to terminal N. Mechanism 1G will therefore remain in the reverse position.

With relay 1HDR energized by current of reverse polarity, relay 1FYR will now be energized by a circuit passing from terminal B, through contacts 55 and 56 of relay 1HDR, and the winding of relay 1FYR to terminal N. With relay 1FYR energized, relay 1FR will be energized by a circuit passing from terminal B, through the front point of contact 42 of relay 1FYR, and the winding of relay 1LOR to terminal N. The high resistance winding of relay 1LOR will now remain energized by its pickup circuit previously traced through the front point of contact

43 of relay 1AR, and lamp 1E, as previously described.

During the periods when contact 52 of relay 1FR is closed at its back point, capacitor c will be charged by its circuit passing from terminal B, through the front point of contact 40 of relay 1LOR, a resistor r, capacitor c, and the back point of contact 52 of relay 1FR to terminal N.

During the periods when contact 52 of relay 1FR is closed at its front point, capacitor c will be discharged through the high resistance winding of relay 1LOR by a circuit passing from capacitor c, through resistor r, front point of contact 40 of relay 1LOR, high resistance winding of relay 1LOR, and the front point of contact 52 of relay 1FR, back to capacitor c. Since the high resistance winding of relay 1LOR is already energized by its circuit through the front point of contact 43 of relay 1AR, the discharge of capacitor c will perform no useful function at this time.

I shall now assume that, while the first train is on section 3T, a second eastbound train enters section 0T, deenergizing relay 1AR, as previously described, thereby opening the pickup circuit for the high resistance winding of relay 1LOR through the front point of contact 43 of

relay 1AR. The high resistance winding of relay 1LOR will now be energized, from capacitor c by the stick circuit previously traced, while contact 52 of relay 1FR is closed at its front point, and the low resistance winding of relay 1LOR will be energized when the contacts of relay 1FR are closed at their back points. The circuit for energizing the low resistance winding will pass from terminal B, through the front point of contact 40 of relay 1LOR, contact 41 of relay 1FR, low resistance winding of relay 1LOR in multiple with asymmetric unit i, back point of contact 43 of relay 1AR, and lamp 1E to terminal N.

The high resistance winding of relay 1LOR is therefore energized by a stick circuit while contact 52 of relay 1FR is closed at its front point, and the low resistance winding of relay 1LOR is energized by a stick circuit when contact 41 of relay 1FR becomes closed, so that relay 1LOR retains its front contact 40 closed at the front point. During the periods while contact 41 of relay 1FR is closed, lamp 1E is energized in series with the low resistance winding of relay 1LOR, and therefore lamp 1E is periodically lighted. Since mechanism 1G is now in its reverse position, signal 1S will display its flashing yellow light aspect.

When the first train leaves section 3T, relay 3AR will again become energized by its circuit previously described, so that lamp 3E will again be connected in series with the high resistance winding of relay 3LOR, causing lamp 3E to be extinguished. Relay 3HR will now be energized, and relay 3HDR will be deenergized while the train occupies the block 4T east of signal 4S, so that mechanism 3G will be operated to its reverse position by a circuit which is similar to the first reverse control circuit previously traced for mechanism 1G.

With relay 3HR again energized, relay 1HDR will be energized by current of normal polarity in the circuit first traced for this relay. Mechanism 1G will therefore be operated to its clear position, and relay 1FYR will become deenergized, causing relay 1FR to also be deenergized. With relay 1AR deenergized on account of the second train on section 0T, lamp 1E will now again be lighted by its circuit previously traced through the back point of contact 42 of relay 1FYR and the back point of contact 43 of relay 1AR, and signal 1S will now again display the steady green light aspect.

With contacts 23 and 24 of relays 3HR and 2HR, respectively, now closed, relay 2HDR will be energized by current of reverse polarity in a circuit which is similar to the circuit previously traced for relay 1HDR, as long as the first train occupies the block 4T east of signal 4S. With relay 2HR energized and relay 2HDR energized by current of reverse polarity, mechanism 2G will now be energized by current of reverse polarity in a circuit which is similar to the second circuit previously traced for energizing mechanism 1G by current of reverse polarity.

I shall next assume that again a first train occupies section 3T, and that a second train has entered section 0T, causing signal 1S to display the flashing yellow light aspect, as previously described. I shall assume further that while the first train is still on block 3T, lamp 3E burns out. With lamp 3E burned out, relay 3LOR will be deenergized. Relay 3HR is, however, still deenergized on account of relay 3TR being deenergized, so that the burning out of lamp 3E will cause no change in the indication displayed by signal 1S.

When the first train now leaves block 3T, relay 3LOR will remain deenergized on account of lamp 3E being burned out, and therefore relay 3HR will remain deenergized, causing signal 1S to continue to display the flashing yellow light aspect instead of changing to the steady green light aspect, as previously described, when the first train left section 3T with lamp 3E not burned out.

When the second train now enters section 1T, signal 1S will be controlled to display the steady red light aspect as previously described when the first train entered section 1T. Now, however, signal 2S will not dis-

play either the steady green light aspect or the flashing yellow light aspect since relay 2HDR is deenergized on account of relay 3HR being deenergized, which is in turn deenergized on account of relay 3LOR being deenergized. With relay 2HDR deenergized, mechanism 2G will now be energized by current of reverse polarity, and relay 2FYR will be deenergized, so that signal 2S will display the steady yellow light aspect.

The operating rules of railroads usually require that a dark signal be obeyed as a stop signal. The arrangement shown in the accompanying drawings for displaying restrictive indications in the rear of a dark signal aids in removing the operating hazard of a sudden brake application resulting from an unexpected dark signal.

The control and operation of the modified form of apparatus shown in Fig. 2 is similar to that described for the apparatus associated with signal 1S in Figs. 1a and 1b. The circuits by which lamp 1E and the low resistance winding of relay 1LOR are normally energized by alternating current and by which they become energized by direct current when the source of alternating current fails are believed to be obvious in view of the description of the operation of the form of apparatus shown in Figs. 1a and 1b.

I have described the operation of the apparatus for a few typical traffic situations. It is believed that, in view of the foregoing description, the operation of the apparatus for any other possible traffic situation can be readily followed by referring to the accompanying drawings, without further description.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In a three-block four-indication signal control system in which each signal includes a lamp and is controlled by a train approaching it in the direction for which the signal governs traffic movements to display an aspect comprising a steady green light or a flashing yellow light or a steady yellow light or a steady red light according as the first three blocks in advance of the signal are unoccupied or the first two blocks in advance are unoccupied while the third block is occupied or the first block in advance is unoccupied while the second block is occupied or the first block in advance of the signal is occupied respectively, the combination comprising, a flashing yellow control relay for each signal, means responsive to a train occupying the third block in advance of each signal while the first two blocks in advance are unoccupied for energizing the corresponding flashing yellow control relay, a flasher relay for each signal which if energized closes and opens its front and back contacts alternately at a frequency which may be on the order of forty times per minute, means including a front contact of the flashing yellow control relay for each signal for effecting energization of the flasher relay for the same signal, a slow release lightout relay for each signal having a first winding with a high resistance which may be of the order of 1000 ohms and having a second winding with a low resistance which may be of the order of 0.58 ohms, an approach control relay for each signal normally energized but becoming deenergized in response to a train occupying the first block in the rear of the first block in advance of the corresponding signal, means controlled by a front contact of the approach control relay for each signal for energizing the first winding of the lightout relay for the same signal in series with the lamp for the same signal, means controlled by back contacts of the approach control relay and the flashing yellow control relay for each signal in series with each other and with

the second winding of the lightout relay for the same signal for lighting the lamp for the same signal, and stick circuits for the first and second windings of each of said lightout relays controlled by means including front and back contacts respectively of the flasher relay for the same signal and the stick circuit for said second winding including the lamp for the same signal for maintaining said lightout relays energized when said same signal is displaying its flashing yellow aspect.

2. In a three-block four-indication signal control system in which each signal includes a lamp and is controlled by a train approaching it in the direction for which the signal governs traffic movements to display an aspect comprising a steady green light or a flashing yellow light or a steady yellow light or a steady red light according as the first three blocks in advance of the signal are unoccupied or the first two blocks in advance are unoccupied while the third block is occupied or the first block in advance is unoccupied while the second block is occupied or the first block in advance of the signal is occupied respectively, the combination comprising, a flashing yellow control relay for each signal, means responsive to a train occupying the third block in advance of each signal while the first two blocks in advance are unoccupied for energizing the corresponding flashing yellow control relay, a flasher relay for each signal which if energized closes and opens its front and back contacts alternately at a frequency which may be on the order of forty times per minute, means including a front contact of the flashing yellow control relay for each signal for effecting energization of the flasher relay for the same signal, a slow release lightout relay for each signal having a first winding with a high resistance which may be of the order of 1000 ohms and having a second winding with a low resistance which may be of the order of 0.58 ohm, an approach control relay for each signal normally energized but becoming deenergized in response to a train occupying the first block in the rear or the first block in advance of the corresponding signal, control means including front and back contacts of the approach control relay for each signal for effecting energization of said first and second windings respectively of the lightout relay for the same signal in series with the lamp of the same signal, and stick circuits for said first and second windings of each of said lightout relays controlled by means including front and back contacts respectively of the flasher relay for the same signal and the stick circuit for said second winding including the lamp for the same signal for maintaining said lightout relays energized when said same signal is displaying its flashing yellow aspect.

3. In a three-block four-indication signal control system in which each signal includes a lamp and is controlled by a train approaching it in the direction for which the signal governs traffic movements to display an aspect comprising a steady green light or a flashing yellow light or a steady yellow light or a steady red light according as the first three blocks in advance of the signal are unoccupied or the first two blocks in advance are unoccupied while the third block is occupied or the first block in advance is unoccupied while the second block is occupied or the first block in advance of the signal is occupied respectively, the combination comprising, a flashing yellow control relay for each signal, means responsive to a train occupying the third block in advance of each signal while the first two blocks in advance are unoccupied for energizing the corresponding flashing yellow control relay, a flasher relay for each signal which if energized closes and opens its front and back contacts alternately at a frequency which may be on the order of forty times per minute, means including a front contact of the flashing yellow control relay for each signal for effecting energization of the flasher relay for the same signal, a slow release lightout relay for each signal having a first winding with a high resistance

which may be of the order of 1000 ohms and having a second winding with a low resistance which may be of the order of 0.58 ohm, an approach control relay for each signal normally energized but becoming deenergized in response to a train occupying the first block

- 5 in the rear or the first block in advance of the corresponding signal, pickup circuit means for said first and second windings of the lightout relay for each signal including front and back contacts respectively of the approach control relay for the same signal in series with the lamp for the same signal, and stick circuit means for said first and second windings of each of said lightout relays including front and back contacts respectively of the flasher relay for the same signal and the stick circuit means for said second winding including also the lamp for the same signal for maintaining said lightout relays energized when said same signal is displaying its flashing yellow aspect.

4. In a three-block four-indication signal control sys-

- 20 tem in which each signal includes a lamp and is controlled by a train approaching it in the direction for which the signal governs traffic movements to display an aspect comprising a steady green light or a flashing yellow light or a steady yellow light or a steady red light according

- 25 as the first three blocks in advance of the signal are unoccupied or the first two blocks in advance are unoccupied while the third block is occupied or the first block in advance is unoccupied while the second block is oc-

- cupied or the first block in advance of the signal is 30 occupied respectively, the combination comprising, a flashing yellow control relay for each signal, means re-

- 35 sponsive to a train occupying the third block in advance of each signal while the first two blocks in advance are unoccupied for energizing the corresponding flashing yel-

- low control relay, a flasher relay for each signal which 40 if energized closes and opens its front and back contacts alternately at a frequency which may be on the order of forty times per minute, means including a front contact of the flashing yellow control relay for each signal for

- 45 effecting energization of the flasher relay for the same signal, a slow release lightout relay for each signal hav-

- 50 ing a first winding with a high resistance which may be of the order of 1000 ohms and having a second winding with a low resistance which may be of the order of 0.58 ohm, an approach control relay for each signal normally energized but becoming deenergized in response to a train occupying the first block in the rear or the first

- 55 block in advance of the corresponding signal, pickup circuit means for said first and second windings of the lightout relay for each signal including front and back contacts respectively of the approach control relay for

- 60 the same signal in series with the lamp for the same signal, and said pickup circuit means for said second winding also including a back contact of said flashing yellow control relay for the same signal, an energy

- 65 storing device for each signal, means including a front contact of the lightout relay for each signal in series with a back contact of the flasher relay for the same signal for charging the energy storing device for the same signal, a stick circuit for the second winding of the lightout relay for each signal controlled by means in-

- 70 cluding back contacts of the flasher and approach control relays for the same signal in series with the lamp for the same signal, and a stick circuit for the first winding of the lightout relay for each signal including front con-

- 75 tacts of the flasher and lightout relays for the same signal in series with the energy storing device for the same signal for maintaining said lightout relays energized when said same signal is displaying its flashing yellow aspect.

5. In a three-block four-indication signal control sys-

a steady yellow light or a steady red light according as the first three blocks in advance of the signal are unoccupied or the first two blocks in advance are unoccupied while the third block is occupied or the first block in advance is unoccupied while the second block is occupied or the first block in advance of the signal is occupied respectively, the combination comprising, a flasher relay for each signal which if energized closes and opens its contacts repeatedly at a given frequency, means responsive to a train occupying the third block in advance of each signal while the first two blocks in advance are unoccupied for energizing the flasher relay for the same signal, a slow release lightout control relay for each signal having a first winding with a high resistance and a second winding with a low resistance, an approach control relay for each signal normally energized but becoming deenergized in response to a train occupying the first block in the rear or the first block in advance of the corresponding signal, pickup circuit means for the first and second windings of the lightout relay for each signal controlled by means including front and back contacts respectively of the approach control relay for the same signal in series with the lamp for the same signal, stick circuit means for said first and second windings of each of said lightout relays controlled by means including front and back contacts respectively of the flasher relay for the same signal and the stick circuit means for said second winding including the lamp for the same signal for maintaining said lightout relays energized when said same signal is displaying its flashing yellow aspect, and a front contact of the lightout relay for each signal included in control means for the next signal in the rear.

6. In a control arrangement for a three-block four-indication signaling system in which a signal for each block is of the type comprising a mechanism and a lamp, in which the mechanism for each signal is controlled by traffic responsive means to occupy a first position if there is no train on any of the first three blocks in advance of the corresponding signal and to occupy a second position if there is a train on the second or the third block in advance of the corresponding signal while there is no train on the first block in advance of the corresponding signal, the combination comprising for each signal, a flasher relay which if energized closes and opens its front and back contacts, alternatively a given number of times per minute, means responsive to a train on the third block in advance of the signal while there is no train on the first or the second block in advance of the signal for energizing the flasher relay for the signal, a slow release lightout relay having a first winding with a high resistance and a second winding with a low resistance, an approach control relay normally energized but becoming deenergized in response to a train on the first block in the rear or on the first block in advance of the signal, pickup circuit means for said first and second windings of said lightout relay controlled by means including front and back contacts respectively of said approach control relay in series with the lamp for the corresponding signal and the pickup circuit means for said second winding also including a contact which is closed by traffic responsive means at all times except when there is a train on the third block in advance of the corresponding signal while there is no train on either the first or the second block in advance of the corresponding signal, stick circuit means for said first and second windings of said lightout relay controlled by means including front and back contacts respectively of said flasher relay for maintaining said lightout relay energized when said first block to the rear of said signal and said third block in advance of said signal are occupied, said stick circuit means for said second winding also including the lamp for said corresponding signal, and a front contact of said lightout relay included in control means for the mechanism of the corresponding signal.

7. In a control arrangement for a three-block four-

indication signaling system in which a signal for each block is of the type comprising a mechanism and a lamp, in which the mechanism for each signal is controlled by traffic responsive means to occupy a first position if there is no train on any of the first three blocks in advance of the corresponding signal and to occupy a second position if there is a train on the second or the third block in advance of the corresponding signal while there is no train on the first block in advance of the corresponding signal, the combination comprising for each signal, a flasher relay which if energized closes and opens its front and back contacts alternately a given number of times per minute, means responsive to a train on the third block in advance of the signal while there is no train on the first or the second block in advance of the signal for energizing the flasher relay for the signal, a slow release lightout relay having a first winding with a high resistance and a second winding with a low resistance, an approach control relay normally energized but becoming deenergized in response to a train on the first block in the rear or on the first block in advance of the signal, pickup circuit means for said first winding of said lightout relay controlled by means including a front contact of said approach control relay in series with the lamp for the corresponding signal, stick circuit means for said first and second windings of said lightout relay controlled by means including front and back contacts respectively of said flasher relay for maintaining said lightout relay energized when said first block to the rear of said signal and said third block in advance of said signal are both occupied, said stick circuit means for said second winding also including the lamp for said corresponding signal, and a front contact of said lightout relay included in control means for traffic governing means.

8. In combination, a stretch of railway track divided into a first and a second and also a third block arranged in the order named, a signal for governing traffic movements in a given direction over said blocks in said order, said signal comprising a mechanism and a lamp, traffic responsive means for effecting operation of said signal mechanism to a first position if said three blocks are unoccupied and to a second position if said second or said third block is occupied while said first block is unoccupied, a flasher relay which if energized closes and opens its front and back contacts alternately a given number of times per minute, means responsive to a train on said third block while there is no train on said first or said second block for energizing said flasher relay, an approach control relay normally energized but becoming deenergized in response to a train approaching said signal in said given direction within a given distance in the rear of said signal, a slow release lightout relay having a first winding with a high resistance and a second winding with a low resistance, a pickup circuit for said first winding controlled by a front contact of said approach control relay and including said lamp of said signal, stick circuits for said first and second windings including front and back contacts respectively of said flasher relay and said stick circuit for said second winding also including said signal lamp for maintaining said lightout relay energized when said first block to the rear of said signal and said third block in advance of said signal are both occupied, and a front contact of said lightout relay included in control means for traffic governing means.

9. In combination, a railway signal comprising a mechanism and a lamp for governing traffic movements in a given direction over a first and a second and also a third railway track block in the order named, traffic responsive means for effecting operation of said signal mechanism to a first position if all three of said blocks are unoccupied and to a second position if said second or said third block is occupied while said first block is unoccupied, a flasher relay which if energized repeatedly closes and opens its front and back contacts alternately

at a given frequency, means controlled by said traffic responsive means for effecting energization of said flasher relay only if said third block is occupied while said first and second blocks are unoccupied, a slow release lightout relay having a first winding with high resistance and a second winding with low resistance, an approach control relay normally energized but becoming deenergized in response to a train approaching in said given direction within a given distance in the rear of said signal, a pickup circuit for said first winding including a front contact of said approach control relay in series with said signal lamp, a stick circuit for said second winding including back contacts of said flasher and approach control relays in series with said signal lamp for maintaining said lightout relay energized when a train traveling in said given direction is within said given distance to the rear of said signal and said third block in advance of said signal is also occupied, an energy storing device, a circuit controlled by a back contact of said flasher relay for charging said energy storing device, a stick circuit for said first winding including said energy storing device and a front contact of said flasher relay for maintaining said lightout relay energized when a train traveling in said given direction is within said given distance to the rear of said signal and said third block in advance of said signal is also occupied, and a front contact of said lightout relay included in control means for traffic governing means.

10. In a control system for a signal for governing traffic movements in a given direction over a given stretch of railway track, said signal comprising a mechanism and a lamp, in which control means is provided for at times effecting operation of said mechanism to a given first

position and for at other times effecting operation of said mechanism to a second position, the combination comprising, a flasher relay which while energized closes its front and back contacts alternately at a given frequency, means controlled by said control means for energizing said flasher relay when said control means is in condition for effecting operation of said mechanism to said second position, a slow release lightout relay having a first winding with high resistance and a second winding with low resistance, an approach control relay normally energized but becoming deenergized in response to a train approaching said signal within a given distance on said track in said given direction, a pickup circuit for said first winding controlled by a front contact of said approach control relay and including said signal lamp, a stick circuit for said second winding controlled by back contacts of said flasher and approach control relays and including said signal lamp for maintaining said lightout relay energized when said flasher relay is energized and said approach control relay is deenergized, a stick circuit for said first winding controlled by a front contact of said flasher relay, and a front contact of said lightout relay included in control means for traffic governing means.
